FIG. 5.

FIG. 6.

Montford Morrison
INVENTOR

UNITED STATES PATENT OFFICE.

MONTFORD MORRISON, OF CHICAGO, ILLINOIS.

X-RAY APPARATUS.

Application filed April 21, 1923. Serial No. 633,712.

The present invention comprises a new apparatus for holding X-ray tubes particularly when they are in operation.

Some of the objects of my invention are, 5 first; to provide an improved means for holding X-ray tubes particularly while in operation, second; to provide an improved means for cooling an X-ray tube while in operation, third; to provide an improved 10 means for stabilizing the tube operation, fourth; to provide improved electrical protection for animal life from the high voltage circuit, fifth; to provide adequate X-ray protection for animal tissue not intended 15 to be exposed to the X rays, sixth; to provide improved voltage protection for the X-ray tube, seventh; to provide a substantially coronaless electric circuit in accordance with my application Serial No. 460,835, 20 filed April 21, 1921, on rectifiers for electric current.

As a means for holding X-ray tubes while in operation, in the prior art they have been clasped along their glass stems by materials 25 of different specific inductive capacity than the medium surrounding the glass tube, and since the said glass stems contain electrodes which have a high potential difference above ground impressed upon them, there results 30 a concentration or distortion of the electric field within and about the glass tube in a neighborhood of not only these clasps but in the neighborhood of all other materials incorrectly disposed, I have discovered.

In the prior art these clasps and other 35 materials incorrectly disposed prevent not only the proper cooling of the glass due to their deflecting the cooling medium from its proper course but also said clasps prevent the glass from expanding and contracting in accordance with its natural inclination, thus causing fractures and other damage, I have discovered.

The use of clasps and improperly shaped 45 objects disposed in the neighborhood of the glass tube, in distorting the field within and about the X-ray tube, tend to cause or exaggerate erratic behavior in the operation of the said tube, I have discovered.

In the prior art the high tension electrical 50 circuits of such X-ray apparatus as herein disclosed, have not been adequately pro-

tected by ground shields or sufficiently remotely disposed to avoid danger from electrical shock, I find. 55

The use of X-ray-opaque shields, of forms different from those which are symmetrical about the axis or axes of the electrodes, are ineffective and inefficient with respect to their apparent value, judged from their 60 thickness and material, I find.

X-ray tubes operated at very high voltages are very sensitive and liable to rupture by voltages above those for which the tube is constructed; and due to surges, traveling waves and the like, I find that voltage protective devices remotely disposed from the 65 tube are inefficient and inadaquate.

X-ray tubes operated at very high voltages, particularly those which are operated 70 for long periods of time, are placed in holders, containers and, or circuits, which due to the formation of corona give out great volumes of nitrous acid and ozone, 75 which are very nauseating to animal life and very active chemically, which results in not only the production of sickness but also in the destruction of property.

It is, among other things, with the above 80 mentioned disadvantages of prior art in mind that I have made the invention and discovery set forth in this disclosure, and among the objects of my invention are the substantial reduction in those disadvantages 85 above set forth in the prior art and an improved X-ray apparatus as a whole.

In the accompanying drawings, Fig. 1, 90 is an illustrative sketch of one form of my invention as viewed in its side elevation in part section, and Fig. 2 is a section taken through a right plane at *a b* in Fig. 1, Figs. 3 and 4 are cross-section details of the tube terminal sockets in Fig. 1, and Figs. 5 and 6 are respectively end and side views of a table 95 which I may use in the therapeutic application of my invention.

Referring to Figs. 1 and 2, the form of 100 my invention illustrated therein consists of means 1 for supporting the tube holder 2 and in the form shown, the part 2 consists physically of a hollow cylinder having one or more openings 3 for the emission of X-rays, and one or more openings 4 for the possible intake or output of a cooling

medium caused to flow by means of a device 5. The hollow cylinder 2 is provided with end shields 6 and 7, which close or nearly close the otherwise open ends of said hollow cylinder.

Alternating current source 33 feeds current to step up transformer 34 and the circuit of which current may be supplied with a switch 35, said step up transformer is connected up to preferably a rectifier 36 and to high voltage conductors 37 as disclosed in my patent application, Serial Number 460, 835, filed April 12, 1921.

In the case of the use of a hot cathode X-ray tube, alternating current generator 33 or other means may supply regulator 38 and X-ray tube filament heating transformer 39, heating current for the filament of the X-ray tube 16, as is well understood in the art.

The high voltage electric current is led into and out of said hollow cylinder by means of terminals 8 and 9 which have conventional insulators 10 and 11. Terminal parts 8 and 9 are electrically connected to spheres or other surfaces of large curvature 12 and 13, which in turn are connected to terminals 14 and 15 of X-ray tube 16, thus forming the electric circuit from terminal 9, for instance, to surface 13, thence through the tube to surface 12, and then to terminal 8, and through whatever high voltage or combination of voltage circuits that may be required or used externally with my invention.

Fig. 3 is a cross section of the surface-figure 13, and consists of a general surface as disclosed in my before-mentioned patent application of any form whatever, and into one side of which figure is a socket or receptacle 17, for receiving and holding one of the X-ray tube terminals, and comprises means 18, 19 and the like for supplying one or more insulated electrical conductors as that X-ray tube terminal which it receives and holds may require.

Fig. 4 is a cross section of the surface-figure 12, and I have illustrated a form of tube socket or receptacle which may be combined with or used separately with the construction illustrated in Fig. 3, and which socket or receptacle provides longitudinal adjustment and compensation for longitudinal positioning and longitudinal variations of the tube, as well as automatic means for allowing for the longitudinal expansion and contraction of the tube during heating and cooling, and without imparting unnecessary mechanical strains upon the tube. Fig. 4 comprises a surface of any general form as aforementioned for Fig. 3, and a receptacle 20, which has adjustment longitudinal with the tube and means, such as the spring or elastic device 21, for taking up the slack out of the longitudinal adjustment as

well as affording a cushioning effect for the longitudinal expansion and contraction of the X-ray tube.

It will be appreciated by those skilled in the art to which my invention appertains, upon reference to Fig. 1, that I may use at aperture 3, an X-ray-translucent material or filter, and make my apparatus otherwise liquid-tight, except at such places as where I might desire the liquid to escape, thereby utilizing a liquid cooling and insulating medium, or I may use a device substantially as illustrated, and utilize air or other gases as insulating and cooling mediums.

Attention is directed to the fact at this point that X-ray tubes and the like, operated in holders of the prior art, which have clasps about the stems, and other materials in the near vicinity of the glass envelope, have the inner walls of the said glass envelope more or less non-uniformly deposited with metallic vapor and the like, which distort the electrostatic field within and about the said X-ray tube, causing more or less erratic or exaggerated misbehavior in the operation of the said tube, and sometimes rupture and other disastrous results.

Referring again to Fig. 1, it will be appreciated that electrically an X-ray tube is substantially a small electrical conductor formed by electrode 22, electron emission stream 23 and anode 24, and if I choose to operate my apparatus with a gaseous cooling medium, and before the X-ray tube has been operated in a prior art tube-holder, the effect of the glass envelope around the tube would not, because of the substantial identity of the specific inductive capacity of the space within the tube and without the tube, have any material influence upon the distribution of the electrostatic field within the tube, in the absence of substantial gas ionization within the tube.

So that in order to operate a tube under its most favorable conditions the electrostatic field within the tube and about it should be as uniformly distributed as possible, and in the case of a tube having electrodes lying in the same straight line, such as X-ray tube 16 illustrated in Fig. 1, I can, in view of the conditions set forth in the foregoing, produce a very uniform field around the tube, by surrounding the electrodes 22 and 24 with a hollow cylinder 2, thus in effect establishing a field of force substantially that obtained by concentric cylinders which are known to mathematical and physical science to give uniform fields for any equi-potential service therein.

However, let it be understood that in disclosing my invention it is only incidental that a concentric cylinder is illustrated because of the fact that the X-ray tube illustrated herein has its terminals in one straight line, but in reality my invention

calls for a substantially more uniform field about the tube than heretofore used, and if some other form of tube be employed, the form of my electrostatic shield will change 5 in accordance with the physical figure, dimensions and directions of the electrodes such as to produce a more uniform field than heretofore employed.

It will be appreciated that the absence of 10 impediments around and about the X-ray tube 16, cooling medium of whatever form it may be and in whatever direction or directions it may flow, will produce more effective cooling by unimpaired contact with, 15 flow by, or to and from the walls of the X-ray tube envelope, the terminals and whatever means or devices are supplied wth or form a part of the tube terminals or electrodes, to effect or improve the cooling of 20 the target and other parts of the tube.

With the form of my invention illustrated herein, I employ a blower or exhaust fan 3, which causes the flow of air or other gases about the terminal or cooling surface 12, 25 around the stems and spherical surface of the X-ray tube, thence around the surface 13, and thence substantially uniformly through the opening 4, or the flow consid- 30 ered vice versa.

It is not fundamental to my invention to have the cooling medium flow in any particular direction, or to have it taken in or exhausted at any particular place or places, but to have it flow freely about the envelope 35 and, or the terminals of the tube.

However, I consider as a preferable blower, one blowing in the longitudinal direction of the tube, and as illustrated on the anode terminal or cooling surface and substantially 40 uniformly around the tube; thence in a direction longitudinal with the tube, and finally through an opening which is substantially symmetrical as a figure of revolution taken about the axis of the tube. It will be 45 appreciated that the cooling medium forced in by means of 5 against the anode cooling surface 12 is deflected throughout the whole cylinder 2 and does not necessarily have its whole heat contained or carried along in 50 the immediate neighborhood of the walls of the glass envelope of the X-ray tube.

I have spoken largely of glass tubes, but of course my invention is applicable to any form of X-ray or vacuum tube envelope 55 which as a whole or as a part possesses the adequate insulation which is necessary to the construction of the tube.

I have found that by surrounding an X-ray tube with an electrostatic shield of such 60 a form as to give a substantial uniform electric field around the tube, there is a decided stabilizing action in this construction over and above what would be experienced by clasping the tube about its stems, or having 65 other improperly designed or shaped objects

in the near vicinity of the tube during operation.

I have found that an X-ray tube operated in a holder of the design employed in the prior art may become erratic and uncertain in its behavior and operation, and the same said tube when placed within electrostatic shield of the kind which I have invented, becomes more stable, more certain in its operation and gives a longer life to 70 the tube, which is an important factor in consideration of the present high cost of X-ray tubes, and in particular where they are used for almost continuous service in the therapeutic destruction of cancerous tissue 75 and the like, on human beings. This stabilizing action also provides a more satisfactory and efficient treatment due to the lack of interruption, variations in the treatment and the like. 80

In the disclosure of my invention let it be understood that I have not invented solely, an improved device for the therapeutic use of X-ray tubes, as it will be appreciated by those familiar with the art to which my invention appertains, that my apparatus is suitable for any and all uses to which high voltage X-ray or vacuum tubes are or may be put. 85

Referring back to Figs. 1 and 2, it will 90 be observed that only the tops or corona guards of terminals 8 and 9 are dangerous electrical conductors, and that nowhere else are electrical conductors exposed or accessible to human touch, and in my invention I 95 so disposed these terminals as to make them inaccessible to physicists, operators or patients by remotely disposing them in such a manner as to render them harmless. Electrostatic shield 2 and electrostatic guards 100 105 and 26 may be all grounded or operated at substantially ground potential, thus eliminating electrical danger.

It will be appreciated, in the absence of a 110 direct metallic grounding of electrostatic shield 2, that the said shield will assume some potential between that of the tube terminals 12 and 13 depending upon the electrostatic capacity between the said terminals 115 12 and 13 and the shield 2, since the terminal 12 forms with electrostatic shield 2 an electrostatic condenser and shield 2 with terminal 13 likewise forms another electrostatic condenser. The potential of shield 2 in the absence of the said ground being at the center plate of two condensers in series, assumes a potential between that of the two said terminals and the potential of said shield 2 will, therefore, depend upon the relative 120 capacities of the two condensers in series together with some influence caused by the wave-form of the impressed electro-motive force and leakage of the circuit. 125

In the use of substantially X-ray-opaque 130 materials for the protection of workers,

operators and patients, against burning of X-rays where the burning is not desired, the effectiveness of the X-ray protection with reference to the weight of the material may be improved by having the X-rays fall upon this X-ray opaque material at such an angle as would make this angle more constant than has been heretofore employed by the prior art. That is to say, if one thickness of material is used over any considerable range of surface, the more uniform the extent of the angle of the X-rays over this surface, the more efficient is the X-ray opaque material with reference to its total weight. Thus by employing a means for accomplishing this I have improved the X-ray protective device of the prior art. The ends of my devices such as at the opening 4, are so baffled as to prevent the escapement of X-rays at any such point.

Electrostatic shields, 25 and 26, are of such a form and thickness and have such apertures so disposed as to prevent the escape of any X-rays which originate in the neighborhood of the focal spot from passing through the insulating materials and thence through the openings through which the insulating materials protrude. In some cases I make terminals 10 and 11 with concentric substantially X-ray-opaque-material sheets, of such forms as are commonly employed in the so-called condenser terminals, which further prevent the escape of any X-ray through the apertures of the corona guard 25 and 26.

On all extremely high voltage circuits, surges, traveling waves and the like are apt to produce voltages at one part of the high voltage circuit different from that of another part, and voltage protective devices remotely disposed from the tube terminals do not always give adequate voltage protection, in view of which I have associated an adjustable parallel spark-over gap, 27, very closely with the tube terminal, thereby improving the voltage protection of the tube over the prior art, by having a substantial, definite safety gap closely associated with the terminals of the X-ray tube.

All those familiar with the protracted use of very high voltage X-ray tubes as well as those familiar with the operation of very high voltage apparatus, appreciate the extreme disadvantage of the continuous generation of large quantities of ozone and nitrous acid by the high voltage conductors in other parts of the circuit.

Following the invention disclosed with my before mentioned patent application I have provided the same means in this invention for substantially reducing this corona and nitrous acid. It will be appreciated, particularly by those familiar with the art of X-ray therapy, that patients become extremely nauseated, sometimes unbearably so, by the production of the aforesaid ozone, and

nitrous acid, and that in many installations it has been necessary to construct an elaborate means for exhausting the air rapidly from the room in which the X-ray tube is operated, or provide elaborate systems for removing the ozone and nitrous acid from about, and from the neighborhood of, the X-ray tube. Both ozone and nitrous acid are very active chemically and react chemically not only upon the delicate parts of the human anatomy but upon the metals and furnishings in the room sufficiently so as to impair their use and value.

I have discovered that if the corona guard 2, surfaces 12 and 13, terminals 8 and 9, and other electrical parts are of such proper design and proportions substantially as set forth in my before mentioned patent application, the corona and nitrous acid are so materially reduced that the air in room in which the X-ray tube is operated may be circulated by means of a blower or exhaust fan 5, within the room itself, without the detection of any undesirable or harmful amount of ozone and nitrous acid, and the tube may be operated continuously in an apparatus built after my invention, in a hospital treatment room, or the like, without the slightest inconvenience, and with the perfect comfort of the patient, which is a striking improvement over the prior art.

As illustrative of how my invention is used in hospitals and the like, I have shown a table illustrated in Figs. 5 and 6, which may be raised and lowered by a motion established at 28, and transmitted by means of mechanical devices, such as 29, 30 and 31, and the like. The patient lies on the table surface 32, and the said table is placed with such reference to aperture 3 in Fig. 1 as will allow the X-rays to impinge upon the desired anatomical part of the patient's body.

Tube holder 2 may be revolved bodily about the axis of the tube.

It will be appreciated upon reference to Fig. 2, and in general, that the tube-holder and patient may be moved in such ways and by such means with reference one to the other, as to give the desired X-ray dosages at such angles and in such positions as the operator may desire.

What I claim is:

1. In an X-ray device, means for supporting an X-ray tube and surface-characteristic means for substantially eliminating the production of corona about said tube at operating voltage thereof.

2. In an electrical circuit, the combination of an X-ray tube, and an electrostatic shield external of said tube at a potential between that of the electrodes of the said tube and having surface-characteristic-means for substantially eliminating the production of corona at operating voltages of said tube.

3. In a high voltage apparatus, an electrostatic shield, an X-ray tube with surfaces and terminals co-operative with said electrostatic shield, having geometrical figures 5 of such physical contour as to substantially eliminate ionization at operating voltages of the said apparatus, thereby practically eliminating corona.
4. In an apparatus of the class described 10 comprising an electrostatic shield, an X-ray tube co-operative with said electrostatic shield and an electric potential source for causing such co-operation, said tube and said shield having surfaces of curvature sufficiently remote from the curvatures which 15 generate substantial corona at the applied potential under operation to substantially eliminate objectionable corona.
5. In a high voltage apparatus comprising 20 an X-ray tube, means for holding same, said tube and said means comprising a plurality of parts being provided with surface-characteristic-means for collectively reducing the density of the electrostatic field determining the corona-formation point of said field, at 25 operating voltages of said tube.
6. In a high potential apparatus of the class described comprising an X-ray tube, an electrostatically co-operative shield and an 30 electrical potential source causing such co-operation, certain parts of said tube and said shield being of opposite polarity when the said tube is being operated, and being spaced laterally and longitudinally, and having 35 surfaces of curvature sufficiently near the corona point and sufficiently removed from the spark-over point of the electrostatic field of the said curved surfaces in their predetermined space relations, to prevent substantial 40 formation of corona in and about the said apparatus under operating voltages thereof.
7. In an X-ray device, means for supporting an X-ray tube and a cylindrical electrostatic shield disposed thereabout and forming an X-ray protective screen for the X-rays generated by the said tube, and comprising means for improving the electrostatic-field-uniformity about the walls of the said tube. 45
8. An electric discharge apparatus comprising the combination with an electric discharge device, of a hollow body surrounding said device, said body having such dimensions and such form relative to the shape 50 of said device and being so disposed with respect thereto as to equalize the electrostatic field distribution in and about said apparatus when high potentials are impressed upon said device.
9. An electric discharge apparatus comprising the combination with an electric discharge device, of an electrostatic shield surrounding said device, said shield having such dimensions and such form relative to the shape of said device and being so dis- 55
- posed with respect thereto as to equalize the electrostatic field distribution in and about said apparatus when high potentials are impressed upon said device.
10. In an X-ray device, means for supporting an X-ray tube and an electrically-conductive X-ray protective shield about said tube and at a potential between that of the electrodes of said tube, substantially concentrically cylindrical with the axis of the electrodes of said tube and remotely disposed therefrom, whereby intense electrostatic-field distribution about the walls of the said tube is substantially eliminated. 70
11. In an X-ray device, a hollow cylindrical member of electrically conductive material at ground potential, electrical insulating wall bushings projecting through said member and supporting an X-ray tube of fixed over-all dimensions within aforesaid member and with space relations between said tube and said shield, whereby the electrostatic field about the said tube is substantially equalized. 80
12. In an X-ray device, an X-ray tube, means for supporting same within a substantially concentric hollow cylindrical electrostatic shield and X-ray absorbing screen, wall bushings passing through said shield and electrical conductors in said bushings supplying excitation energy for said tube from a high potential source, and means for supply and exhaust of cooling medium to said tube; whereby said tube may operate within equalized electrostatic fields and said medium may flow unobstructedly to and by the walls of the said tube. 90
13. In an X-ray device, means for supporting an X-ray tube, a cylindrical electrostatic shield of electrically conductive material at a potential between that of the electrodes of said tube and surrounding said tube and high tension terminals remotely disposed from the field of X-ray action and passing through said shield. 105
14. In a device of the class described, an X-ray tube with members co-operating electrostatically with neighboring members of an electrostatic shield at differences of electrical potential, said tube and said members integral over all configurations presenting rounded contours on substantially all portions effectively within the high potential electrostatic field caused by the said differences of electric potential, whereby corona is substantially eliminated, one member forming a terminal for the said tube and being hollow. 110
15. In a device of the class described, an X-ray tube and X-ray tube supporting members having configurations presenting a rounded contour on substantially all portions effectively within the high potential electrostatic field, said members comprising hollow conducting shells. 125
- 130

16. In a device of the class described, X-ray tube-terminal supporting members comprising shells with rounded sections and recessed to receive terminals of the X-ray tube.
- 5 17. In an electric discharge apparatus, the combination with an electric discharge device, of electrically conductive means for supporting said device and means associ- ated with said supporting means permitting expansion and contraction of said device 10 while maintaining electrical contact therewith, said supporting means having a geometric configuration of such a nature as to prevent corona.

MONTFORD MORRISON.
